VACUUM TUBE GETTER

Bernard Bernstein, West Orange, N.J., assignor to Nuclear Corporation of America, Inc., Denville, N.J., a corporation of Delaware

Application April 16, 1958, Serial No. 728,900

4 Claims. (Cl. 206—4)

The present invention relates to vacuum tube getters and more particularly to a highly efficient vacuum tube getter in which the metallic getter deposit may be confined within a predetermined region.

Getters have been employed for many years in the manufacture of vacuum tubes in order to improve the vacuum within such tubes. As the frequencies at which vacuum tubes are operated increased, it became necessary to prevent the gettering material from depositing on the envelope of the tube since such deposits introduce into the circuit associated with the tube appreciable electrical leakage and also produce damage of the vacuum tube envelopes as a result of radio frequency heating of the metallic deposits on the inner surface of the envelope.

In an effort to prevent metallic gettering material from becoming deposited on the inner surface of the envelopes of high frequency vacuum tubes, there was developed a getter structure including a hollow glass cylinder having metallic end caps. The end caps have small tabs pressed out from the caps and a getter bar structure was suspended in the glass cylinder between the tabs. The getter structure is mounted within a vacuum tube and heated by radio frequency or other suitable heating means so as to evaporate the gettering material. Vapors tend to travel in a straight line, and therefore, the vapor becomes deposited on the inner surface of the glass cylinder while there is little tendency for the vapor to pass out the openings in the end caps. The aforesaid getter structure is completely effective in preventing any of the gettering material from becoming deposited on the inner surface of the vacuum tube envelope, but its efficiency is quite low since the surface area of the getter material exposed to the gases to be absorbed is less than it had been when deposited upon the envelope of the tube. Further, the small size of the openings in the end caps of the glass cylinder prevents an appreciable circulation of the gases through the cylinder and, therefore, greatly limits the volume of gases which may contact the gettering material when it is flashed.

It is an object of the present invention to provide a getter structure having a large surface area upon which to deposit a metallic gettering material and which further provides for ready access of the gases to be absorbed to the gettering materials.

It is another object of the present invention to provide a getter structure for vacuum tubes having a large surface area upon which vaporized getter material may be deposited and having an outer surface structure which is porous so that gases to be absorbed may readily pass through the envelope and into the region of the gettering material.

In accordance with the present invention, there is provided a getter structure having a hollow and porous sleeve formed of a suitable material such as fiber glass and filled with a thin filamentary material such as glass wool or other non-oxidizable, wool-like material. Disposed along the axis of the sleeve or cylinder is a getter bar which may be maintained in proper relationship to

2

the sleeve by the glass wool in which the bar is embedded. Metallic members or ribbons extend outwardly from the bar through suitable openings in the sleeve and are secured to opposed arms of a stationary yoke. In operation, the getter bar is heated and the gettering material supported thereby is vaporized and becomes dispersed throughout the glass wool so that an extremely large surface area of gettering material is provided. The porous sleeve is of such a porosity that during subsequent flashing of the getter material, the gases to be absorbed may pass through the porous sleeve and also through the openings in the ends of the porous sleeve into its interior and through the glass wool material where the gases contact the gettering material.

15 The glass wool provides a large surface on which the gettering material may become deposited when it is vaporized and this in conjunction with the porous sleeve prevents any of the gettering material from escaping from the sleeve and becoming deposited upon the interior surface 20 of the envelope of the vacuum tube. The glass wool material should have a sufficient density to prevent an appreciable amount of the gettering material from becoming deposited on the inner surface of the porous sleeve, since this might close the passages through the sleeve and 25 materially reduce the efficiency of the structure.

It is, therefore, another object of the present invention to provide a getter structure having a fine, filamentary material upon which gettering material may be deposited and having a porous sleeve or enclosure for physically 30 confining the filamentary material while permitting gases to pass therethrough into the region of the filamentary material.

The above and still further objects, features and advantages of the present invention will become apparent upon consideration of the following detailed description of one specific embodiment thereof, especially when taken in conjunction with the accompanying drawings, wherein:

Figure 1 is a schematic vertical diagram of an electron tube including the getter structure of the present invention;

Figure 2 is a longitudinal cross-section of the getter structure of the present invention; and

Figure 3 is an end view of the getter structure of the present invention.

45 Referring specifically to Figure 1 of the accompanying drawings, there is provided a vacuum tube having an envelope 1 and a base 2. The tube is further provided with a press 3 for supporting mounting rods 4 and 6. The rods 4 and 6 extend upwardly from the press 3 and are 50 adapted to support the active elements of the tube disposed within an anode structure 7, also supported on the rods 4 and 6.

A leg member 8 of a yoke 9 is secured, as by welding or other suitable means, to one of the rods, such as the 55 rod 6, and supported between arms of the yoke 9 is the getter structure of the present invention which is generally designated by the reference numeral 11.

Referring now specifically to Figures 2 and 3 of the accompanying drawings, the getter structure 11 comprises a hollow generally cylindrical envelope 12 fabricated from porous material such as fiber glass. The two ends of the envelope 12 are provided with generally circular apertures 13 and the interior of the envelope is substantially filled with a non-oxidizable, fine, filamentary material 14, such as glass wool. Positioned approximately along the axis of the porous envelope 13 is a conventional getter bar 16 which has secured at its opposite ends metallic supporting arms 17 and 18, respectively. The arms 17 and 18 extend outwardly through the apertures 13 and are secured as by brazing to the arms of the support yoke 9, as illustrated in Figure 1 of the accompanying drawings. The envelope 12 is maintained in a fixed posi-

tion with respect to the getter bar 16 by the mass of filamentary material 14. The getter bar 16, which is a commercially available structure, is provided with a suitable gettering material such as magnesium, tantalum, aluminum and barium and mixtures of barium and aluminum. The gettering material may be deposited in a cup supported by the bar 16 or in the type of bar illustrated in the accompanying drawings may constitute a coating 19 deposited on the bar.

In operation the getter is heated to vaporization temperature and the vapor distributed throughout the glass wool 14 disposed within the envelope 12. Heating of the gettering material may be effected by a number of well known methods; for instance, subjecting the tube to a radio frequency magnetic field which induces current in a circuit constituting the bar 16, the support arms 17 and 18 and the yoke 9. The glass wool 14 and the porous envelope 12 combine to prevent the vaporized gettering material from escaping to the inner walls of the envelope 1 and, therefore, prevent subsequent malfunctioning of the tube due to high frequency leakage and heating. When gettering action is desired in addition to that provided during the period that the material is in the vapor state, the gettering material may be flashed and due to the large surface area of the glass wool 14 and the porosity of the sleeve 12, the gettering action is extremely efficient. Specifically, the glass wool 14 provides a very large surface area for the vaporized gettering material and, therefore, subsequently provides a large surface area of contact between the gettering material and the gases during flashing. Further, the efficiency of the getter is enhanced due to the porosity of the envelope 12 which permits ready flow of the gases through the porous envelope into the region of the glass wool. Since glass wool is a relatively porous material it presents no impediment of flow of the gas therethrough and contact with the multiple surfaces provided thereby. The very large surface area of the glass wool not only increases the chemical reaction rate between the gas and the gettering material when the latter is flashed, but it also greatly increases the subsequent absorption of gases by the gettering material during the effective life of the tube. The outer porous sleeve as indicated above, confines the gettering material, during vaporization, to the region of the glass wool, permits gas to enter the region of the wool and confines the getter flash within itself.

In the structure described above, the getter bar 16 supports the remainder of the getter structure since it is

embedded in the filamentary material 14, which in itself has sufficient strength to maintain a given shape and, therefore, acts as a support for the sleeve 12. However, if desired, spoked end supports for the sleeve 12 may be secured to the supporting arms 17 and 18. The spokes would not materially reduce the flow of gases through the ends of the sleeve since they take up little of the total space across the opening.

The invention has been described as employing a porous sleeve substantially filled with a filamentary material. The filamentary material is relatively self-supporting or at least tends to maintain a given shape and, therefore, the sleeve 12 may be completely open ended. Such a structure permits a ready flow of air from end to end through the cylinder and, therefore, it is not absolutely essential that the sleeve 12 be porous. The utilization of a non-porous sleeve will produce a distinct reduction in the efficiency of the structure, but the efficiency of such a structure is still greater than that provided by the aforesaid prior art apparatus.

While I have described and illustrated one specific embodiment of my invention, it will be clear that variations of the general arrangement and of the details of construction which are specifically illustrated and described may be resorted to without departing from the true spirit and scope of the invention as defined in the appended claims.

What I claim is:

1. A getter structure comprising a porous, hollow cylinder, a body of filamentary material disposed in said cylinder, a bar disposed approximately along the axis of said cylinder and embedded in said body of filamentary material, and a quantity of gettering material supported by said bar, said gettering material being in the form of a coating on said bar.
2. A getter structure as defined in claim 1 wherein said cylinder is of fiber glass material.
3. A getter structure as defined in claim 1 wherein said cylinder is provided with an opening at each end.
4. A getter structure as defined in claim 3, wherein two arms are provided which support said bar and extend outwardly through said openings.
